UNITED STATES PATENT OFFICE.

FRED L. MCGAHAN, OF INDIANAPOLIS, INDIANA.

LOCOMOTIVE FEED-WATER SUPPLY.

SPECIFICATION forming part of Letters Patent No. 466,360, dated January 5, 1892.

Application filed April 27, 1891. Serial No. 390,585. (No model.)

To all whom it may concern:

Be it known that I, FRED L. MCGAHAN, a citizen of the United States, residing at Indianapolis, in the county of Marion and State 5 of Indiana, have invented a new and useful Improvement in a Locomotive Feed-Water Supply, of which the following is a specification.

My invention relates to improved means for furnishing pure water to the boiler of a 10 locomotive and for heating the cars connected thereto.

The object of my improvement is to provide, in connection with a locomotive feed-water heater, (for which I have made application for United States Letters Patent, which 15 application was filed March 2, 1891, Serial No. 383,456,) means whereby that portion of the exhaust-steam from the engines which is diverted from the smoke-stack to the feed- 20 water heater is after passing through said heater used to heat a car or cars attached to the locomotive, and the water of condensation resulting therefrom is returned to the locomotive-boiler, thus reducing the amount of 25 water necessary to be taken aboard and preventing the formation of scale in the boiler, all as hereinafter fully set forth.

The accompanying drawings illustrate my invention.

30 Figure 1 is a side elevation of a locomotive with my improvements attached thereto. Fig. 2 is a cross-section, on a larger scale, through the smoke-box and the valves in the exhaust-nozzles. Fig. 3 is a sectional view through 35 one of the exhaust-valves on the line *x*, Fig. 2. Fig. 4 is a longitudinal section through the tender at *w*. Fig. 5 is a top plan of the tender. Fig. 6 is a cross-section through the same on the line *y*, Fig. 5. Fig. 7 is a side 40 elevation of a portion of the locomotive and tank, showing the mechanism for pumping water from the tank into the boiler of the locomotive. Fig. 8 is a detail view showing the covering of the exposed steam-pipes. Fig. 9 45 is a longitudinal section through a passenger-car, showing the arrangement of the heating-pipes, radiators, and return-pipes. Fig. 10 is an under side view of the same. Fig. 11 is a plan of a modified form of the system of 50 steam pipes and radiators as applied to a mail or express car. Fig. 12 is a cross-section

on the line *z*, Fig. 11. Fig. 13 is a detail view of the main steam-pipe connections between cars, one-half being in section. Fig. 14 is a side view of the pipe connections for the return of the condense-water to the tank.

In the drawings, 1 is the smoke-box of the locomotive, into which extend exhaust-nozzles 2, which communicate with the exhaust-passages 3 of the steam-chests. At the base of 60 and within the nozzles 2 are valves 4, (shown in Figs. 2 and 3,) arranged in chambers, each having two discharge-ports 5 and 6, the first of which opens into one of the nozzles 2, which discharges into the stack. The other ports 6 65 open into the horizontal pipes 7, to which are connected the pipes 8 on either side of the locomotive. The valves are segments formed in the manner shown in Fig. 3, and are rigidly secured to rods 9, whose inner ends work 70 in bearings in the walls of the valve-chambers, and their outer ends pass through the outer walls of such chambers and out through the center of the horizontal pipes 7, where they are connected rigidly to short cranks 10, 75 which are pivoted to rods 11, whose opposite ends are in turn pivoted to cranks 12, which at about their centers are pivoted to suitable brackets attached to the sides of the locomotive. The lower ends of the cranks 12 engage 80 valve-rods 13 of the engines, so that in the backward and forward movements of such rods the valves 4 in their chambers will operate to alternately open and close the ports 5 and 6, thus allowing a portion of the exhaust-steam to escape through the nozzles 2 and up the stack, thus creating a draft, the rest of the steam passing into the pipes 7 and 8, the pipes 8 extending back on either side of the locomotive, and having suitable flexible 85 90 couplings 14 to allow for any lateral movement of the train they pass through the drip-chambers 15 of the tank and turn upward into oil-separating chambers 16.

In the upper part of the chambers 16 pipes 95 17 extend downward and enter the heating and purifying tank 23, where they join each other and have a common outlet 18 on the under side, directly above a central open settling chamber or well 19, around which are 100 the covered settling-chambers 20, communicating therewith. The settling-chambers are

connected together in series by openings 21, which are alternately high and low, the last one through which the feed-water passes being a high one and opening into the chamber 22, which has a perforated bottom above the drip-chambers 15, into which the feed-water from the heater flows.

In the upper part of the heating and purifying tank 23 are suitably arranged and supported pans 24, and that part of the exhaust-steam that is not condensed by coming in contact with the water in said pans escapes from the chamber through the outlet 25 and into the pipe 26, which extends above the tank for the purpose of connecting with the cars in the rear.

For use in warm weather, when no heat is required in the cars, I have arranged just below the pipe 26 and within the tank a vertically-sliding plate or valve 27, operated by screws 28 from above. Said valve when drawn up closes the outlet through the pipe 26 and allows the free passage of the exhaust-steam from the heating and purifying tank 23 into the condensing-pipes 89, arranged on the outside of the tender, the construction of which is fully set forth in my before-mentioned pending application.

Just in front of the heating and purifying tank 23 is the main water-tank 29 of the tender. In this tank is a pump 30, which is operated by connection with an eccentric on one of the axles of the rear truck. A discharge-pipe 31 extends from this pump into the top of tank 23, and it has a branch 32, which discharges into the main tank. Valves 33 are arranged in these discharge-pipes and are controlled as hereinafter described. The construction up to this point is essentially the same as that shown in my above-mentioned application.

For the purpose of utilizing that portion of the exhaust-steam which is not condensed in passing through the heater and purifier I employ the following means: I arrange beneath the tender and below the level of the drip-chambers 15 a well or auxiliary tank 37, which communicates through openings 38 on each side with said drip-chambers. Auxiliary tank 37 is provided with an open vertical tube 36, which extends from a point near the bottom of the well to the top of the main tank. A float 35 is arranged to move easily in this tube, and this float is connected through a lever 34 with the valves 33 in such a manner that a single movement of the lever will open one of the valves and close the other, thus controlling the amount of water delivered to the heating-chamber from the main tank by the amount of water in the lower tank. The short pipe 26, leading from the top of the tank 23, is connected to the main heating-pipe of the first car by the connection shown in Fig. 13, which consists of a central pipe 60, having its ends loosely secured in the ends of expansion-joints 61, of well-known form, and the

opposite ends of these expansion-joints fit loosely the outsides of elbows 62 and bear against a rib on each, so that in case of accident to the cars the connections will separate readily. The elbows 62 are removably connected by locking-joints 63 to the main steam-pipe 64 on the car and pipe 26 of the tank. Like connections are made between the heating-pipes of the several cars of a train.

Each car is provided with a system of steam circulation, as follows: The steam-pipe 64 leads into the top of the car, as shown in Fig. 9, and extends down to the floor and along the car on either side within the foot-boards, 80 the side pipes 65 being within the car and connected together at their ends by the cross-pipes 66, in which are three-way valves 67 for regulating the direction of the steam-supply. Pipes 66 are connected with each other and with a series of radiators 71 by a pipe 69, having at its ends three-way valves 70. An outlet-pipe 68 leads from the rear cross-pipe 66 out through the top of the car. The radiators 71 are secured to the under side of the car 90 with their upper surface exposed to the interior of the car, and the central one is arranged so that the condense-water from the others flows into the central one. Arranged on each side of the central radiator are a pair of condense-water reservoirs 73, which are connected with the radiator by short pipes 72. Said reservoirs are connected by expansion-joints with drain-pipes 74, which lead at the forward end of the car to the drip-chambers 15 on the tender and which lead at the rear end of the car to the drain-pipes of the next car. The drain-pipes 74 are connected together between the cars by a connection shown in detail in Fig. 14, which consists of a pair of universal 105 couplings 86, connected by a pair of telescoping tubes 88 and a light chain 89.

In the mail-car (shown in Fig. 11) a pair of central radiators 78 are arranged on opposite sides of the center of the car, the inlet-pipe 64 extends down through the floor of the car, and all of the distributing-pipes are on the under side. These pipes consist of the two outer ones 77, which are connected with the radiators 78, and the central pipe 79, which 115 connects the radiators 80, arranged at each end of the car, with each other and with the cross-pipes 81, which connect the side pipes 77 at both ends. In this car I have arranged the condense-water reservoirs 73 between the 120 central radiators, and they are connected to the radiators by short pipes. The said reservoirs discharge through pipes 82, having expansion-joints therein, and expansion-joints 83, which are pivoted to the bottom of the car 125 at 84 into the drain-pipes 74, leading to either end of the car. The outer ends of the drain-pipes are supported loosely in stirrups 85, which are of sufficient width to permit the side movement of the pipes in turning curves. 130 The drain-pipes 74 convey all of the water of condensation formed in the steam-circulating

systems of the cars into the drip-chambers 15 of the tender, and from thence the water is drained into the auxiliary tank or well 37. The boiler of the locomotive is supplied with 5 water from the well 37 by means of a pump 39, there being one on each side of the tank or well. The pump-plunger 41 is operated by means of an eccentric 53 on the rear driving-shaft of the locomotive, which is connected 10 with the plunger by the connecting-rod 54, having a grooved end 57 and a detachable tip 50, and sliding in bearings 55, the lever 43, pivoted to the tender, and the connecting-rod 42.

15 The amount of water drawn by the pump from the tank 37 is controlled by means of a hand-lever 46, which, through its connections with the rod 47, pivoted to the bell-crank lever 48, regulates the admission of water to 20 the pump through its suction-pipe. The lever 48 is pivoted at its center to the side of the tank 37 and its lower arm to a short rod 49, which operates the suction-pipe valve 50 and the air-valve 51 of the pump. Through 25 the lever in the cab the suction-valve may be opened and the air-valve closed simultaneously, or the reverse, or when only a partial supply of water is desired each may be only partly opened, according to the movement of 30 the lever. The water passes to the boiler from the pump through the pipe 40.

In operation that portion of the exhaust-steam which passes through pipes 7 and 8 into the heating and purifying tank 23 is 35 used to heat the feed-water therein. The steam escaping from the heater through pipe 26 passes to the steam-circulating system of the car, and the resulting water of condensation collecting in the reservoirs 73 is finally 40 discharged through drain-pipes 74 and drip-chambers 15 into the auxiliary tank or well 37. This condense-water constitutes, after the boiler has once been filled, the principal 45 source of supply for the boiler, the loss by evaporation and leakage being made up and the supply supplemented by the water from the main tank, which is first passed through the heating and purifying chamber by means 50 of the pump 30. When there is sufficient 55 water in tank 37, float 35 is raised and the water from pump 30 is discharged through the branch 32 into the main tank again; but when the water is nearly exhausted in tank 37 the float falls and the water from said 55 pump is discharged through pipe 31 into the heater, from whence it finds its way, after purification, into tank 37.

I claim as my invention—

1. The combination of the locomotive, the 60 water-tank attached thereto, the separate water heating and purifying chamber arranged in said tank, the pipes arranged to conduct the steam from the exhaust-ports of the locomotive to said chamber, the auxiliary tank arranged to receive the water from the heating and purifying chamber, the pump ar- 65

ranged to deliver the water from the main tank to the heating-chamber, the valve arranged in the discharge-pipe of said pump, mechanism, substantially as shown and de- 70 scribed, whereby said pump is operated continuously during the movement of the locomotive, and the float arranged in the auxiliary tank and connected with said valve, whereby the amount of water delivered to the heating 75 and purifying chamber is controlled by the amount of water in the auxiliary tank, substantially as set forth.

2. The combination of the locomotive, the feed-water heater connected therewith so as to receive steam therefrom, the auxiliary tank arranged below said heater so as to receive the water therefrom, the car attached to the locomotive, a system of steam circulation mounted on said car and connected at one 85 end with the steam-outlet of said heater, and a system of drain pipes and passages connecting said steam-circulating system with said auxiliary tank, all arranged substantially as set forth, whereby the steam from the locomotive is used first to heat the feed-water and then to heat the car, and the water from the heater and the water from the steam-circulating system on the car are both collected in the auxiliary tank. 90

3. The combination of the locomotive, the main water-tank thereof, the feed-water heater connected therewith and arranged to receive the steam from the locomotive, the auxiliary tank arranged below said heater so as to receive the heated water therefrom, the car attached to the locomotive, a system of steam circulation mounted on said car and connected at one end with the steam-outlet of said heater, a system of drain pipes and passages connecting said steam-circulating system with said auxiliary tank, the pump arranged to discharge the water from the main water-tank into the feed-water heater, the float mounted in the auxiliary tank, and intermediate connecting mechanism connecting said float and the discharge-pipe of the pump, whereby the discharge of water therefrom into the heater is controlled by the amount of water in the auxiliary tank, all substantially as set forth. 105

4. The combination of the locomotive, the main water-tank thereof, the feed-water heater connected therewith and arranged to receive the steam from the locomotive, the auxiliary tank arranged below said heater so as to receive the heated water therefrom, a system of steam circulation connected at one end with the steam-outlet of said heater, drain pipes and passages connecting said steam-circulating system with said auxiliary tank, 125 the pump arranged to discharge the water from the main water-tank into the feed-water heater, the float mounted in the auxiliary tank, intermediate connecting mechanism connecting said float and the discharge-pipe 130 of the pump, whereby the discharge of water therefrom into the heater is controlled by the

amount of water in the auxiliary tank, and the pump arranged to draw the water from the auxiliary tank and discharging it in to the locomotive-boiler, all arranged to co-operate substantially as set forth, whereby the boiler is supplied, primarily, with distilled water, which supply is supplemented by water from the main tank, substantially in the manner specified.
